UNITED STATES PATENT OFFICE

ERIC OLLE SCHJOLIN, OF BIRMINGHAM, MICHIGAN, ASSIGNOR TO GENERAL MOTORS CORPORATION, OF DETROIT, MICHIGAN, A CORPORATION OF DELAWARE

SLEEVE VALVE ENGINE

Application filed September 8, 1927. Serial No. 218,282.

This invention relates to sleeve valve engines.

When the exhaust of a sleeve valve engine is discharged from one side of the cylinder, that side of the cylinder and of the sleeve valve or valves becomes heated more than the other side, and, consequently, the sleeve or sleeves and the cylinder expand more at that side, which may cause excessive friction 10 and in some cases permanently warp the sleeve or sleeves and/or the cylinder. It is an object of this invention to provide a means to equalize the heating of the sleeve or sleeves and the cylinder.

It is another object of the invention to provide, in combination with means for equalizing the heating of the sleeve or sleeves and the cylinder, means for heating the air supplied to the carburetor.

It is another object of this invention to provide certain improvements in manifolds, and, more specifically to provide a manifold having in an integral structure separate passages for the combustible mixture entering the cylinder and for the exhaust gases leaving the cylinder, and a stove attached to the exhaust side of the manifold to heat the air sucked into the carburetor.

Other objects will appear in the course 30 of the following specification, of which the accompanying drawings form a part.

In the drawings—

Fig. 1 is a transverse cross section through a cylinder of a sleeve valve engine in which 35 my invention is embodied; and

Fig. 2 is a diagrammatic side elevation of the upper portion of the engine.

In the drawings, the reference character 1 indicates the cylinder block of the engine 40 which is mounted on and secured to the base or crankcase 2. The cylinder walls 3 are water jacketed, as indicated at 4, providing spaces, such as 5, for the circulation of cooling water.

Arranged to slide in the cylinder 3 is the outer sleeve valve 6, and arranged to slide in the outer sleeve valve 6 is the inner sleeve valve 7. Secured to the sleeves 6 and 7, respectively, are the lugs 9 and 10 to which 45 connecting rods are adapted to be connected

to operate the sleeves substantially in the manner shown in United States Patent No. 1,136,143, issued April 20, 1915 to C. Y. Knight. The piston 8 is slidably mounted within the inner sleeve valve 7, and is adapted to be connected to the crankshaft through the ordinary connecting rod.

The reference character 11 indicates the cylinder head which is attached to the block 1 by bolts, such as 12. The cylinder head 60 has an inwardly projecting portion 13, between which and the cylinder walls the sleeves 6 and 7 are adapted to slide, and is water jacketed, as indicated at 14, providing a space 15 for the circulation of cooling 65 water.

The cylinder is provided with an exhaust port 16 which communicates with an exhaust manifold 17 secured to the block by means, such as studs and nuts 18 and 19, respectively. The outer sleeve 6 is provided with an exhaust port 20, and the inner sleeve 7 with an exhaust port 21 in their sides adjacent the exhaust port 16. The exhaust ports 20 and 21 are adapted to be brought into registration with each other and the exhaust port 16 at the proper time to allow discharge of the exhaust gases from the cylinder into the exhaust manifold.

In the side of the cylinder opposite the exhaust port 16 is provided an intake port 22. In the sides of the sleeves 6 and 7 adjacent the port 22 are provided intake ports 23 and 24, respectively. The intake ports 23 and 24 are adapted to be brought into registration with each other and with the intake port 22 at the proper time to admit the charge from the intake manifold 25 to the cylinder.

In the side of the cylinder opposite the exhaust port 16, and spaced below the inlet port 22, is provided an auxiliary exhaust port 26. In the sides of the sleeves 6 and 7 adjacent the port 26 are provided auxiliary exhaust ports 27 and 28, respectively. The auxiliary exhaust ports 27 and 28 are adapted to be brought into registration with each other and with the auxiliary exhaust port 26 at the proper time to allow discharge of the exhaust gases from the cyl- 100

inder into the auxiliary exhaust manifold 29. As can be seen from the drawing, the exhaust ports 20 and 21 in the sleeves will register with each other and the cylinder exhaust port 16 at the time that the auxiliary exhaust ports 27 and 28 in the sleeves register each other and with the auxiliary cylinder exhaust port 26.

Due to the fact that both of the exhaust ports 16 and 26 are open to allow discharge of the exhaust gases at the same time, a portion of the exhaust gases will be discharged from each port. And due to the fact that the hot exhaust gases are discharged partly at one side and partly at the other side of the sleeves, the heating of the sleeves will be equalized and, consequently, unequal expansion of the sleeves and its consequent troubles will be prevented.

20 The intake manifold 25, which communicates with intake port 22, and the exhaust manifold 29, which communicates with the auxiliary exhaust port 26, are formed of one piece of metal to which the reference character 30 is applied. The upper and lower side walls 31 and 32 of the integral intake and exhaust manifold are provided respectively with lugs 33 and a flange 34 through which and the gasket 39 extend bolts 35 and 36, respectively, which secure the manifold 30 to the block 1. In order to provide separate passages for the incoming charge and the outgoing exhaust gases, the manifold is divided into an upper passage 25 (the intake manifold) and a lower passage 29 (the exhaust manifold) by the partition 37 which is provided with a foot 38 bearing on the gasket 39.

To the lower side of the part 30 is secured a stove, in the form of a stamping 41, by means such as the bolts 36 and 42. Extending downwardly into this stove and integral with the lower side 32 of the manifold 30 are fins 40. The stamping 41 is preferably open at its ends to allow free entrance of air thereto and is provided at a suitable point with a conduit 43 leading to the carbureter air intake.

The air entering the carbureter has first to pass through the stove 41 where it comes into contact with the wall 32 of the exhaust manifold and the fins 40 attached thereto. The wall 32 and the fins 40 are, of course, heated by the exhaust gases and the air passing through the stove is heated by contact with these heated surfaces. The fins have the function of providing more heated surface for the air passing through the stove to come into contact with.

50 In the carbureter, the hot air, of course, becomes mixed with the fuel, and, because it is hot, the mixture is much more intimate, as is desirable. After leaving the carbureter, the fuel and air mixture passes into 55 the intake conduit 45 and then into the in-

take manifold 25, where, due to the fact that it comes into contact with the wall 37 which is heated by the exhaust gases, it is again heated and any possibility of separation of the two constituents eliminated. 70

Thus the air is heated before entering the carbureter and so has no difficulty in taking up its full fuel charge, and, since the mixture of air and fuel is heated just before it enters the cylinder, separation of the two constituents of the fuel is prevented and it is assured that the fuel and air will be intimately mixed when they enter the cylinder. Thus the auxiliary exhaust conduit provides a simple means for supplying heated air to the carbureter air intake, making unnecessary the provision of special passages in the cylinder block or a separate conduit for leading gases from the exhaust manifold to the intake manifold and carbureter. 85

As may be seen by reference to Fig. 2, the auxiliary exhaust manifold 29 discharges into the auxiliary exhaust pipe 44 and, thence, the exhaust gases pass to a muffler or the atmosphere. 90

I claim:

In an internal combustion engine, a cylindrical casing having an exhaust port opening through the wall thereof, a second exhaust port opening through the wall thereof at a point diametrically opposite the first exhaust port, and an intake port opening through the wall thereof at a point adjacent one of said exhaust ports, a pair of sleeve valves provided with exhaust ports and an intake port within the casing for controlling said casing ports, and means for operating said sleeve valves so as to bring one of the exhaust ports therein into registration with one of the exhaust ports in the casing at substantially the same time the other exhaust port therein is brought into registration with the other exhaust port in the casing. 105

In testimony whereof I affix my signature.

ERIC OLLE SCHJOLIN.
